CLAIM

The ornamental design for a light as shown and described.

DESCRIPTION

FIG. 1 is a perspective view of a light showing my new design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

In the drawings, the broken lines depict portions of the light that form no part of the claimed design.

1 Claim, 7 Drawing Sheets
